UNITED STATES PATENT OFFICE.

ROBERT JOY, OF SAN FRANCISCO, CALIFORNIA.

FIRE AND GAS DEFENSE SYSTEM.

1,277,728.

Specification of Letters Patent. Patented Sept. 3, 1918.

Application filed April 25, 1917. Serial No. 164,589.

To all whom it may concern:

Be it known that I, ROBERT JOY, a citizen of the United States, residing at the city and county of San Francisco and State of California, have invented new and useful Improvements in Fire and Gas Defense Systems, of which the following is a specification.

The system herein described may be known as the fire and gas system.

This system for military defense consists of an entrance tunnel which can be constructed one, two or three miles back of forts, buildings or lines of defense. The entrance tunnel leads into a shaft, the size and depth of which will be determined according to the nature of the ground. At the bottom of said shaft there will be a series of tunnels constructed to suit the surface lines of defense. The first parallel tunnel entered from the bottom of said shaft will be known as the "third line tunnel"; the second tunnel entered from the bottom of the shaft will be known as the "second line tunnel"; and the third line tunnel will be known as the "dummy tunnel."

The invention includes containing tanks, piping, valves, pumps and details of construction which will be hereinafter more fully explained by reference to the accompanying drawings, in which—

Figure 1 is a view showing the chambers at the bottom of the shaft and the tunnels and connection with the shaft.

Fig. 2 is a vertical section of the shaft, chamber, and the entrance tunnel.

Fig. 3 is a cross section on line 3—3 of Fig. 2.

Fig. 4 is a cross section on line 4—4 of Fig. 1.

The entrance tunnel H consists of store and sleeping rooms 2 which can be made in sections and out of cast steel. The inner end of this tunnel opens into the upper end of a vertical shaft E from the bottom of which extends the tunnel G. 3 is a machine gun for the protection of said entrance tunnel H. 4 is a half-inch pipe attached to a hand and power pump 5, located at the bottom of the shaft. From thence it leads to the mouth of the entrance tunnel H and is attached to a regulating valve and a spark battery (not shown), so that when a pressure of fifteen pounds or more is in said pipe it will automatically open said

valve and make a contact with said battery which will produce a spark and ignite gasoline and immediately cover the mouth of the entrance tunnel H in a sheet of flame. This same half-inch pipe will also carry 60 anhydrous ammonia which will also envelop the mouth of the tunnel H with ammonia gas, and render an entrance by the enemy impossible. If the ammonia gas should fail to protect the mouth of the 65 tunnel H, use gasoline; if gasoline should fail, use the machine guns. A cast steel door is located in a convenient place in said entrance tunnel H, so that when ammonia gas is used the door could be closed to keep 70 the gas from blowing in on the defenders of said tunnel.

29 is an air duct leading to all parts of the system for ventilation; 6 is a cast steel support to firmly secure the I-beam construction 7 and enable it to withstand heavy shocks without crumbling; and 8 is a platform built around the shaft E. Above this shaft is a protective structure which may be made in any suitable manner and covered 80 with a layer of soil 10 and sod 9. As here shown it is formed as follows: 11 is reinforced concrete; 12 represents steel I-beam; 13 is an attachment for hoisting machine; and 14 represents tie rods for bonding the 85 I-beams together, which can be constructed to provide the greatest possible resistance against the modern shell. The I-beams 12 and the reinforced concrete 11 will be constructed according to the nature of the 90 ground.

The numerals 15 designate gasoline tanks, the location, capacity, construction and installation will be determined by the nature or condition of the lines of the defense and the nature of the ground. The same disposition will be made of the ammonia tanks 16. The valve, pipes and bypasses are so constructed and attached to the gasoline tanks 15, ammonia tanks 16 100 and oil tank 17 that they will enable the engineer to pump out any one tank for repairs in case of leakage. They will also enable the engineer to pump out the discharge side of the system and deposit the 105 various elements, gasoline, refrigerating oil and ammonia into their respective tanks without waste or mixing of the same. The tanks of ammonia and gasoline used for the original charge of the system will be per- 110

manently installed in some convenient place in case of accidents, leaks or changes to be made in the system, so that the engineer could pump out the entire system and de-
5 posit the same in the original tanks.

Each valve and pipe will bear a tag containing its specific duty. 18 is the machine or power pump that will discharge the anhydrous ammonia and gasolene to the 10 surface of the earth, or lines of defense, through the liquid pipe 19. 20 is the sump pump. 22 is the discharge pipe of the sump pump 20 discharging into a sewer constructed for that purpose. 23 is a pumping out 15 pipe; 24 is a suction pipe from the gasolene tanks; 25 represents by-pass pipes; 26 is the discharge pipe to the ammonia tanks 16; 27 is the suction pipe from the refrigerating oil tank; and 28 represents vent pipes for 20 the gasolene and ammonia tanks.

Parallel tunnel C will be known as the third line tunnel and parallel tunnel B will be known as the second line tunnel. 1^a shows a series of ammonia and gasolene 25 expansion valves in the tunnels B and C, connected to the liquid pipe 19 for the purpose of discharging ammonia gas and gasolene to the surface of the earth or the lines of defense.

30 The expansion valve 1^a permits the ammonia gas to pass into the discharge pipe 5^a, and thence to the surface of the earth. 4^a is a by-pass pipe to be used when pumping gasolene, as the ammonia expansion valve 35 1^a would not be large enough to permit a sufficient quantity of gasolene to pass through to flood the surface of the earth. 6^a is a cement foundation built to carry the liquid pipe 19 and is installed directly under 40 each surface discharge pipe, which latter will be bent, as shown at 5^b, before being cemented in the ground to enable said pipe to offer a much greater resistance.

If the discharge pipe 5^a is struck by the 45 enemy's shell, it will be torn and bent and the end of said pipe may be almost closed up. If such should be the case, then the pipe would immediately become an expansion valve which would become still more de- 50 structive to the enemy. If debris should fall on the top or end of the discharge pipe 5^a, in a few moments there would be such a pressure in said pipe as would cut itself a passage and the ammonia gas would escape 55 just the same. The same discharge pipe 5^a will carry the gasolene to the surface of the earth or lines of defense.

13^a indicates a telephone or other signaling station, from which communication may 60 be made to any part of the system. When the officer in charge of the system is ordered to use gasolene, the telephone operator will immediately order the engineer in charge of the machine or pump to change over from 65 ammonia to gasolene. Then each man sta-

tioned at the expansion valves 1^a will be ordered to open the by-pass valve 4^a which will permit large volumes of gas to be poured on the surface of the ground; then orders would be given to throw an incendiary bomb to ignite the gasolene. This would terrify and confuse the enemy and 70 their horses.

If the enemy go around the buildings or forts, they will find the same conditions to 75 deal with at every place. Therefore, it would keep the enemy uncovered and exposed to the guns of the defenders. Furthermore, this system could be installed in 80 mountain passes and narrow confines where the enemy must pass or travel with their big guns and horses and heavy machinery in order to reach the desired point. The enemy could be decoyed into the center of the system and absolutely destroyed in less than 85 two minutes.

The discharge pipes 5^a (Fig. 4) leading to the surface of the earth can be installed about two to three hundred feet apart, figures according to the conditions and lines 90 of defense. One-quarter, one-half or the whole of this system can be used at a time, if found necessary. The engineer in charge could always tell how the system is working by his gage pressure and gage glass, on 95 the ammonia and gasolene tanks, and would govern himself accordingly.

The second line tunnel B is constructed the same as the third line tunnel with the exception that the expansion valves will be 100 installed as shown on the drawing (Fig. 1) or staggered relative to those of the third line tunnel.

The first line tunnel A will be known as the dummy tunnel. If the enemy has discovered the system, in order to destroy it they will tunnel in or on the dummy tunnel 105 A. First, if it is hard ground, it means drilling and blasting; second, if it is medium soft ground, it means timbering. Experience teaches us that there is a law governing sound in and adjacent to the tunnels, and the least sound adjacent to a tunnel of this nature would be heard and discovered very quickly by the guards, such as there would be in war time, and the guards could be trained to be keen on sound. Providing the enemy did approach, and was discovered 115 and located, a hole could be drilled into their chamber or tunnel and a three-eighths extra heavy pipe could be driven in and attached to the blank 7^a (Fig. 1), provided for that purpose, and the ammonia turned on which would render the enemy's tunnel useless. If the enemy has actually entered the dummy 120 tunnel A, the guards would immediately pass out and close the cast steel doors 8^a, 9^a and 10^a.

The expansion valve 11^a would then be turned on to effect a discharge of ammonia from the nozzles 12^a, the ammonia 130

being discharged at two hundred and fifty pounds pressure, traveling faster than the enemy could escape.

If the enemy is approaching the main 5 shaft E at its most vital point, they will first strike the outer reinforced concrete circle or wall F which can be constructed to protect the main shaft.

14^a is the ammonia storeroom; 15^a shows 10 one hundred pound tanks of ammonia already connected to the system; 18 is the ammonia end of the machine or pump; 16^a is the power end of the pump; 17^a is the discharge pipe to the sewer from the power 15 end of the machine 16^a; 21 is the discharge pipe to the gasoline tanks 15 (Fig. 2); and 18^a is the feed pipe to the power end of the machine 16^a, also to the sump pump 20 (see Fig. 2).

20 The surface end or outlet of the discharge pipe 5^a will be capped in time of peace and the system filled with refrigerating oil (see Fig. 4).

A sufficient number of men to operate all 25 parts of the system and the whole being in readiness, in the operation of the system, if the enemy has been victorious upon the surface and is approaching, orders are telephoned down to the officer in charge in the 30 telephone room, who passes the word to the engineer to charge the discharge side of the system. In less than two minutes these orders may be carried out. By this time the 35 enemy may have stormed and captured the forts, etc. Orders then will be communicated to each man stationed at the expansion valve to open and move the indicator to a given point. Immediately the surface of the 40 forts, buildings and lines of defense will be enveloped in the fumes of anhydrous ammonia.

The operation with gasoline will be the same as with ammonia with these additional 45 orders. The engineer will be ordered to change over to gasoline and the men stationed at the expansion valves will be ordered to open by-pass valve 4^a (Fig. 4). When the surface of the earth and forts have been fairly well covered with gasoline, 50 the officer in the telephone room, when notified by the engineer that so many thousand gallons of gasoline have been pumped on the surface of the system, will immediately telephone to the officer in charge of the hidden 55 guns to throw an incendiary bomb on the system and ignite the gasoline which would envelop the system in a sheet of flames.

This system can be installed in mountain 60 passes and narrow confines where the enemy is forced to pass with their big guns and heavy machinery. The enemy could be entrapped in the center of the system and destroyed in a short time. There are oftentimes 65 conditions existing in mountain passes that

this system could be installed, so that when the enemy has been enticed over the lines it would make it impossible to retreat which would mean surrender or be destroyed.

Having thus described my invention, what 70 I claim and desire to secure by Letters Patent is—

1. An underground defense comprising a plurality of upwardly extending discharge pipes, terminating below the top surface of 75 the ground, and means for expelling a poisonous gas through said pipes so that the gas will rise up from the surface of the ground.

2. A defense system comprising a series 80 of concealed parallel tunnels, with intercommunicating passages, a working chamber and storeroom located interiorly to said passages, gates so disposed as to control the passages from the successive tunnels, a receptacle for an asphyxiating medium under compression, pipes leading therefrom to the tunnels and passages, and controlled valves 85 to allow direction and discharge to be effected.

3. In a defense system of the character described, a series of separated tunnels, with an intermediate connecting passage and controlling gates, receptacles for ammonia gas under compression, an interior chamber 95 within which they are located, pipes leading from the receptacles, with nozzles and valves therefor opening into the tunnels, and means located in the chamber to control the discharge within the tunnels.

4. A defensive system of the character described, including a series of parallel, interconnected tunnels with intermediate controlling gates, an interior chamber with ammonia and gasoline tanks, pipes leading 105 therefrom and discharging within the tunnels, and controls located within the inner chamber.

5. A system for defense consisting of a series of underground connecting tunnels, a 110 chamber connected therewith, receptacles for asphyxiating and combustible gases and liquids in the chamber, surface discharge pipes connected with the receptacles, and controlling means therefor.

6. A system of defense comprising a series of underground connected tunnels with a main communicating chamber, asphyxiating gas and combustible liquid receptacles, discharge pipes and pressure apparatus, an entrance tunnel connecting with said main chamber, pipes leading from the receptacles into the entrance chamber, and discharge nozzles in said pipes, with controlling means in the main chamber.

7. In a system of defense of the character described, a central underground chamber with asphyxiating gas and combustible liquid tanks therein, tunnels connected with the bottom of the chamber, pipes connect- 130

ing with both tanks having by-pass passages and leading into the tunnels, discharge nozzles from said pipes to the surface of the ground above, valves controlling the discharge from either or both sets of tanks, and an entrance tunnel communicating with the upper part of said chamber.

8. A system of the character described, including a central subterranean chamber 10 with gas and liquid tanks and connected pipes and pressure devices, a tunnel radiating from the chamber, pipes connecting with both sets of tanks leading to the tunnels, having nozzles within the tunnels and to 15 the surface and by-pass and combining pipes, means to circulate the gas and fluid under pressure, and communicating means between the chamber and tunnels.

9. A defense system comprising a plurality of upwardly extending discharge pipes terminating below the top surface of the ground, a source of fuel arranged beneath the top surface of the ground, and means for discharging the fuel from said 25 pipes into the ground so as to saturate the same for subsequent ignition.

10. In a defense system, a shaft having a laterally extending tunnel intersected by a

plurality of transverse tunnels, means for closing the first tunnel against the outer 30 transverse tunnel, and means for introducing an asphyxiating medium in the tunnels.

11. In a defense system, a shaft having a laterally extending tunnel intersected by a plurality of transverse tunnels, fuel tanks 35 arranged in the upper part of the shaft, gas tanks disposed beneath the fuel tanks, and pipes leading from the tanks through the tunnels, the gas pipes discharging in the latter and the fuel pipes discharging into 40 the ground above the tunnels.

12. In a defense system, a shaft having a laterally extending tunnel intersected by a plurality of transverse tunnels, fuel tanks arranged in the upper part of the shaft, gas 45 tanks disposed beneath the fuel tanks, pipes leading from the tanks through the tunnels, a reinforced roofing above the shaft, and a barrier encircling the shaft.

In testimony whereof I have hereunto set 50 my hand in the presence of two subscribing witnesses.

ROBERT JOY.
